FORK OR SIMILAR ARTICLE

William J. Knope, Jr., Cranston, R.I., assignor to
Gorham Corporation, Providence, R.I.

Filed Mar. 17, 1967, Ser. No. 6,278

Term of patent 14 years

(Cl. D54—12)

FIG. 1 is a front elevational view of a fork or similar article showing my new design;

FIG. 2 is a side elevational view thereof, the fork tines having been omitted for convenience of illustration;

FIG. 3 is a rear elevational view thereof; and

FIG. 4 is an enlarged section taken on line 4—4 of FIG. 1.

The dominant features of the design reside in the handle shown in full lines, the conventional tines being shown in broken lines.

I claim:

The ornamental design for a fork or similar article, as shown and described.
